ABSTRACT

Radiation-curable compositions consisting of (a) an ethylenically unsaturated ester of 1,4,5,6,7,7-hexahalo-2,3-bis(hydroxymethyl)-bicyclo(2,2,1)-5-heptene, tetrahalobenzene-dimethanol, or 2,2'[isopropylidene bis(2,6-dihalophenoxy] dipropylene oxide diol and (b) acyloin, an acyloin derivative, or a halogenated aromatic, alicyclic, or aliphatic hydrocarbon are useful as printing inks, coatings, adhesives, printing plates, and the like.

19 Claims, No Drawings

RADIATION-CURABLE COMPOSITIONS

This invention relates to energy-curing compounds and to processes of energy-curing compounds. More particularly, the invention relates to autopolymerizable ethylenically unsaturated compounds.

The use of photopolymerizable ethylenically unsaturated monomeric materials in coating compositions, adhesives, printing inks, and the like is known. It is also known that such monomeric materials are converted into polymers by the action of radiation and that they will polymerize at an improved rate when exposed to radiation in the presence of a photoinitiator, as in, for example, copending applications Ser. No. 556,568 now abandoned and Ser. No. 685,259.

There are a number of disadvantages connected with the use of a photoinitiator along with the monomer in a photopolymerizable system. In the first place, photoinitiators must be activatable by radiation, such as ultraviolet light, electron beam radiation, or gamma radiation. At the same time they must be thermally inactive at ambient temperatures in order to secure the storage and handling stability of the compositions containing them. In addition, the photoinitiator must be compatible with the monomer and the other ingredients, if any, in the system; for example, the initiator may have only a limited solubility in the selected monomer, thus decreasing the speed of the photopolymerization which to some extent is proportional to the concentration of the initiator in the system. It is also possible for the presence of an initiator to limit the use of other additives in the composition, thus preventing the attaining of the physical properties required for optimum performance in the desired end use.

It has now been found that certain compounds autopolymerize upon exposure to a source of radiation, that is, they photopolymerize in the absence of a photoinitiator at a rate comparable to, or in some cases better than, the speed of previously disclosed monomers in the presence of a photoinitiator.

In general the compounds of this invention are esters of ethylenically unsaturated acids containing halogenated ring compounds having at least one active hydrogen atom left unsubstituted in the nucleus or in a side chain. While this invention will be described broadly in terms of acrylates of chlorinated cyclic compounds, it is to be understood that this invention is not limited thereto. The ester may be a methacrylate or an itaconate as well as an acrylate, or it may be a mixed or a hetero-ester of two or more of these acids. The halogen atom may be bromine, iodine, or fluorine as well as chlorine.

The photopolymerizable compounds of this invention are the esters of halogenated cyclic compounds with acrylic acid, methacrylic acid, itaconic acid, and the like, and their mixtures. The cyclic compound may be any of a large variety of compounds, such as for example

and the like, where X is H or a halogen atom, i.e., Cl, Br, I, or F, and at least one X must be a halogen atom and, in the absence of A or B, one X must be a hydrogen atom; A and B is each —O, —COO, or an alkylene group having one to three carbon atoms; Y and Z is each —H, —OH, —(R-O)aH, or —R where R is a straight chain or branched chain aliphatic radical having one to three carbon atoms and a is an integer of 1 to 10; n and m is each an integer of 1 to 5 and n + m = 6; R₁ and R₂ may be the same or different and represent —H or —CH₃.

Representative of the halogenated ring compounds are 1,4,5,6,7,7-hexachloro-2,3-bis(hydroxymethyl)-bicyclo(2,2,1)

)-5-heptene (known commercially as HET-Diol and sold by Hooker Chemical Company), having the formula

2,3,5,6-tetrachlorobenzene-1,4-dimethanol; 3,4,5,6-
10 tetrachlorobenzene-1,2-dimethanol; 2,4,5,6-
tetrachlorobenzene-1,3-dimethanol, having the formula

a polypropylene oxide adduct of tetrachlorobisphenol A, e.g., 2,2'-[isopropylidene bis (2,6-dichloro-p-phenoxy)]
20 polypropylene oxide diol, having the formula

where n = 0.9; 3,5-dibromosalicylic acid; 5,6,7,8,9,9-hexachloro-1,2,3,4,4a,8,8-octahydro-5,8-methano-2,3-naphthalene dicarboxylic acid; 2,4,5,6-tetraiodo-benzene-1,3-dimethanol; 2,3,5,6-tetrafluoro-benzene-1,4-dimethanol; 35 and the like; and mixtures thereof.

These compounds are converted into esters by any known and convenient means, such as by the ester interchange method of interacting a lower alkyl ester of the acid with the halogenated cyclic hydroxy compound in the presence of a suitable catalyst or by the direct reaction of the cyclic hydroxy compound with, e.g., acrylic or methacrylic acid or in known manner with an acrylyl or a methacrylyl halide. The resulting ester will have at least one halogen atom, and preferably four halogen atoms, in the ring and at least 1 hydrogen atom in the ring or in a side chain.

Specific examples of suitable esters include 1,4,5,6,7,7-hexachloro-bicyclo(2,2,1)-5-heptene-2,3-bis(2,6-dichloro-p-phenoxy); 2,4,5,6-tetrachlorobenzene-1,3-dimethylacrylate; 2,3,5,6-tetrachlorobenzene-1,4-dimethylacrylate; 3,4,5,6-tetrachlorobenzene-1,2-dimethylacrylate; 3,4,5,6-tetrachlorobenzene-1,2-diacrylate; a mixture of the diacrylates of the three isomeric tetrachlorobenzene dimethanols; the esterification product of tetrachlorophthalic anhydride with two moles of 2-hydroxyethylacrylate; the diacrylate of 2,2'-[isopropylidene bis(2,6-dichloro-p-phenoxy)]dipropylene oxide diol; methacrylyl-3,5-dibromosalicylic acid; a polyester of 2,4,5,6-tetrachlorobenzene-1,3-dimethyl-diacrylate; 2,3,5,6-tetrafluorobenzene-1,4-dimethylacrylate; 60 and the like, as well as prepolymers thereof, i.e., dimers, trimers, and other oligomers, and their mixtures.

While the novel esters of this invention may photopolymerize at satisfactory rates in the absence of photoinitiating additives, their photocuring rates can be increased by the addition thereto of a photoinitiator. Examples of suitable photoinitiators include the following: acyloin or an acyloin derivative, such as benzoin, benzoin methyl ether, benzoin ethyl ether, desyl bromide, desyl chloride, desyl amine, and the like; and halogenated aliphatic, alicyclic, and aromatic hydrocarbons and their mixtures in which the halogen atoms are attached directly to the ring structure in the aromatic and alicyclic compounds, that is, the halogen is bonded directly to the aromatic hydrocarbon nucleus, and the halogen atoms are attached to the carbon chain in the aliphatic compounds. The halogen may be chlorine, bromine,

fluorine, or iodine. Examples of such photoinitiators include polychlorinated polyphenyl resins, such as the Aroclors (Monsanto Chemical Company) which in general are polychlorinated diphenyls, polychlorinated triphenyls, and mixtures of polychlorinated diphenyls and polychlorinated triphenyls; polyfluorinated phenyls (E.I. du Pont de Nemours & Co.); chlorinated rubbers, such as the Parlon (Hercules Powder Company); copolymers of vinyl chloride and vinyl isobutyl ether, such as Vinoflex MP-400 (BASF Colors and Chemicals, Inc.); chlorinated aliphatic waxes, such as Chlorowax 70 (Diamond Alkali, Inc.); perchloropentacyclodecane, such as Dechlorane + (Hooker Chemical Co.); chlorinated paraffins, such as Clorafin 40 (Hooker Chemical Co.) and Unichlor-70B (Neville Chemical Co.); mono- and polychloro-benzenes; mono- and polybromobenzenes; mono- and polychloroxylenes; mono- and polybromoxylenes; dichloromaleic anhydride; 1-(chloro-methyl) naphthalene; 2,4-dimethylbenzene sulfonyl chloride; 1-bromo-3-(m-phenoxyphenoxy benzene); 2-bromoethyl methyl ether; chlorendic anhydride; and the like; and mixtures thereof.

These sensitizers or photoinitiators are used to amounts ranging from about 2 to about 80 per cent, and preferably from about 2 to about 70 per cent, of the weight of the total composition.

Irradiation of the autophotopolymerizable compounds can be accomplished by any one or a combination of a variety of methods. The compounds may be exposed, for example, to actinic light from any source and of any type as long as it furnishes an effective amount of ultraviolet radiation, since the compounds of this invention activatable by actinic light generally exhibit their maximum sensitivity in the range of about 1,800 Å. to 4,000 Å., and preferably about 2,000 Å. to 3,000 Å.; electron beams; gamma radiation emitters; and the like; and combinations of these. Suitable sources include carbon arcs, mercury-vapor arcs, fluorescent lamps with special ultraviolet-light-emitting phosphors, argon glow lamps, photographic flood lamps, Van der Graaff accelerators, Resonant transformers, Betatrons, linear accelerators, and so forth.

The time of irradiation is not critical but must be sufficient to give the effective dosage. Irradiation may be carried out at any convenient temperature, and most suitably at room temperature for economic reasons. Distances of the radiation source from the work may range from about one-eighth inch to 10 inches, and preferably from about one-eighth inch to 3 inches.

The autophotopolymerizable compounds of the present invention are suitable for use in the absence of solvents and in the presence of oxygen as vehicles for paints, lacquers, and printing inks which are capable of setting or hardening after printing by exposure to radiation. They are suitable also as compositions and elements for the preparation of photographic images, printing plates, and rolls; as adhesives for foils, films, papers, fabrics, and the like; as coatings for metals, plastics, paper, wood, foils, textiles, glass, cardboard, box board, and the like; as markers for roads, parking lots, airfields, and similar surfaces; and so forth.

The new compounds of this invention are especially interesting because they are non-flammable per se and they impart fire-retardant properties to normally combustible substrates.

In addition to being autopolymerizable, these novel compounds can also serve as photoinitiators in photopolymerizable systems with other monomers, such as for example pentaerythritol triacrylate, pentaerythritol tetraacrylate, trimethylolpropane triacrylate, trimethylethane trimethacrylate, dipentaerythritol hexamethacrylate, and the like, and mixtures thereof.

Various dyestuffs, pigments, plasticizers, lubricants, and other modifiers may be incorporated to obtain certain desired characteristics in the finished products.

When the photopolymerizable compounds of the present invention are used as adhesives with lamina, at least one of the lamina must be translucent when ultraviolet light is used. 75

When the radiation source is an electron beam or gamma radiation, at least one of the lamina must be capable of transmitting high energy electrons or gamma radiation, respectively, and neither is necessarily translucent to light. Typical laminations include polymer-coated cellophane to polymer-coated cellophane films, polymer-coated cellophane to polypropylene, Mylar to a metal substrate such as aluminum or copper, polypropylene to aluminum, and the like.

The photopolymerizable compounds of the present invention may be utilized for metal coatings and particularly for metals which are to be subsequently printed. Glass and plastics may also be printed or coated, and the coatings are conventionally applied by roller or spray. Pigmented coating systems may be used for various polyester and vinyl films; glass; polymer-coated cellophane; treated and untreated polyethylene, for example in the form of disposable cups or bottles; treated and untreated polypropylene; and the like. Examples of metals which may be coated include sized and unsized tin plate.

When used as vehicles for inks, e.g., printing inks, the compound may be pigmented with any of a variety of organic or inorganic pigments, e.g., molybdate orange, titanium white, chrome yellow, phthalocyanine blue, and carbon black, as well as colored with dyes. Stock which may be printed includes paper, clay-coated paper, and box board. In addition, the compositions of the present invention are suitable for the treatment of textiles, both natural and synthetic, e.g., in vehicles for textile printing inks or for specialized treatments of fabrics to produce water repellency, oil and stain resistance, crease resistance, etc.

Photopolymerizable elements of this invention comprise a support, e.g., a sheet or plate, having superimposed thereon a layer of the above-described photopolymerizable compound. Suitable base or support materials include metals, e.g., steel and aluminum plates; sheets; and foils; and films or plates composed of various film-forming synthetic resins or high polymers, such as addition polymers, and in particular vinyl polymers, e.g., vinyl chloride polymers; vinylidene chloride polymers; vinylidene chloride copolymers with vinyl chloride, vinyl acetate, or acrylonitrile; and vinyl chloride copolymers with vinyl acetate or acrylonitrile; linear condensation polymers such as polyesters, e.g., polyethylene terephthalate; polyamides; etc. Fillers or reinforcing agents can be present in the synthetic resin or polymer bases. In addition, highly reflective bases may be treated to absorb ultraviolet light, or a light absorptive layer can be transposed between the base and photopolymerizable layer.

Photopolymerizable elements can be made by exposing to radiation selected portions of the photopolymerizable layer thereof until addition polymerization is completed to the desired depth in the exposed portions. The unexposed portions of the layer are then removed, e.g., by the use of solvents which dissolve the monomer or prepolymer but not the polymer.

The invention and its advantages will be better understood with reference to the following illustrative examples, but it is not intended to be limited thereto. In the examples, the parts are given by weight unless otherwise specified. Unless otherwise indicated, when the ingredient is solid at room temperature, the mixture may be heated to melt the solid ingredient, but generally not above 100° C., or it may be used in admixture with other liquid ingredients. The atmospheric and temperature conditions were ambient unless otherwise noted.

EXAMPLE 1

The following were charged into a 500-ml. three-necked flask equipped with a stirrer, a thermometer, and a Dean-Stark trap with a condenser:

benzene	55 ml.
1,4,5,6,7,7-hexachloro-2,3-bis (hydroxymethyl)-	
bicyclo(2,2,1)-5-heptene (HET-Diol)	243 g.
glacial acrylic acid	144 g.

hydroquinone } (polyzrization inhibitors)	2 g.
copper powder	0.25 g.
methyl sulfonic acid (catalyst)	2 g.

During a 2 hour heating period at $120^{\circ} \pm 3^{\circ}$ C., regulated by the addition of the required amount of benzene, 23 ml. of water was collected from the water-benzene distillate. The reaction mixture was then cooled to 30° – 35° C., and 100 ml. of benzene was added; it was then washed with 400 ml. of 20 percent NaCl solution containing the required amount of 15 percent Na_2CO_3 solution to neutralize the excess acrylic acid. The neutral benzene solution was then washed three times, each with 200 ml. of saturated NaCl solution plus 15 ml. of 10 percent NaOH. The resulting benzene solution was dried over anhydrous K_2CO_3 and then filtered; the benzene was removed from the filtrate by evaporation on a steam bath. The yield of the diacrylate was 280 grams (89 percent of theory based on the HET-Diol). Analysis of the product, 1,4,5,6, 7,7-hexachloro bicyclo(2,2,1)-5-heptene-2,3-bis(methylacrylate), indicated 99.8 percent of non-volatiles and an equivalent weight of 240, based on selective saponification, compared with the theoretical value of 236. The HET-Diol diacrylate was a thick, light tan colored liquid having the refractive index of

$$n_{D1.850} = 1.5545.$$

The rate of the speed of polymerization of the product of Example 1 is compared with the rate of polymerization of pentaerythritol triacrylate in the presence and absence of a photoinitiator in Example 2.

EXAMPLE 2

A 0.25-mil thick sample of the HET-Diol diacrylate prepared in Example 1 was placed on a glass slide and exposed to actinic radiation at a distance of 10 inches from a 1,200-watt Hanovia mercury arc ultraviolet lamp. The following table gives the compositions, the cure times, and the properties of each cured film:

TABLE I

Film Composition, %					
Run	A*	B*	Photoinitiator (Aroclor 4465*)	Cure Time, seconds	Film Properties
1	100	—	—	6.5	tough, flexible
2	70	—	30	2.0	tough, flexible
3	—	100	—	>30	cheesy
4	—	80	20	4.0	brittle, hard
5	—	70	30	3.0	brittle, hard

A* is 1,4,5,6,7,7-hexachloro-bicyclo (2,2,1)-5 heptene-2,3-bis (methylacrylate) (HET-Diol diacrylate)

B* is pentaerythritol triacrylate

Aroclor 4465* is Monsanto Chemical Co.'s mixture of bi- and triphenyls containing 65% of chlorine by weight.

These data show that HET-Diol diacrylate is superior to pentaerythritol triacrylate both in the absence of a photoinitiator (Run 1 vs. Run 3) and in the presence of a photoinitiator (Run 2 vs. Runs 5 and 6).

EXAMPLE 3

The following were charged into a 500-ml. three-necked flask equipped with a stirrer, a thermometer, and a Dean-Stark trap with a condenser:

benzene	65 ml.	70
2,4,5,6-tetrachlorobenzene-1,3-dimethanol	100 g.	
glacial acrylic acid	108 g.	
m-nitrobenzene sodium sulfonate	0.5 g.	
(polymerization inhibitors)		
copper powder	0.125 g.	75
sulfuric acid, 66° Be (catalyst)	2.75 g.	

During a 1 hour heating period at $120^{\circ} \pm 3^{\circ}$ C., regulated by the addition of the required amount of benzene, 12 ml. of water was collected from the water-benzene distillate. The reaction mixture was cooled to 30° – 35° C., and 100 ml. of benzene was added; it was then washed with 200 ml. of 20 percent NaCl solution containing the required amount of 15 percent Na_2CO_3 solution to neutralize the excess acrylic acid. The neutral benzene solution was then washed two times, each with 200 ml. of 20 percent NaCl solution plus 50 ml. of 15 percent Na_2CO_3 solution. The washed benzene solution was dried over anhydrous K_2CO_3 and then filtered; the benzene was removed from the filtrate by evaporation on a steam bath. The yield of the diacrylate was 123 grams (90 percent of theory based on the 2,4,5,6-tetrachlorobenzene-1,3-dimethanol). Analysis of the product, 2,4,5,6-tetrachlorobenzene-1,3-dimethylacrylate, indicated 99.8 percent of non-volatiles and an equivalent weight of 211, based on saponification, compared with the theoretical value of 210. The purified diacrylate was a white crystalline solid having a melting point of 111° – 113° C.

The rate of the speed of polymerization of the product of Example 3 is compared with the rate of polymerization of HET-Diol diacrylate and of pentaerythritol triacrylate in the presence and absence of a photoinitiator in Example 4.

EXAMPLE 4

A 0.25-mil thick sample of the 2,4,5,6-tetrachlorobenzene-1,3-dimethylacrylate prepared in Example 3 was placed on a glass slide and exposed to actinic radiation at a distance of 10 inches from a 1,200-watt Hanovia mercury arc lamp.

TABLE II

Run	Film Composition, %			Photoinitiator (Aroclor 4465*)	Cure Time, seconds	Film Properties
	A*	B*	C*			
6	100	—	—	—	6.5	tough, flexible
7	70	—	—	30	2.0	tough, flexible
8	—	100	—	—	>30	cheesy
9	—	80	—	20	4.0	hard, brittle
10	—	70	—	30	3.0	hard, brittle
11	—	—	100	—	6.5	tough, flexible
12	—	—	70	30	2.0	tough, flexible

A* is HET-Diol diacrylate, the product of Example 1

B* is pentaerythritol triacrylate

C* is 2,4,5,6-tetrachlorobenzene-1,3-dimethylacrylate, the product of Example 3

Aroclor 4465* is a mixture of bi- and triphenyls containing 65% of chlorine by weight.

These data show that 2,4,5,6-tetrachlorobenzene-1,3-dimethylacrylate (Runs 11 and 12) and HET-Diol diacrylate (Runs 6 and 7) behave identically and that each is superior to pentaerythritol triacrylate (Runs 8, 9, and 10), particularly in the absence of a photoinitiator (6.5 seconds to cure for each of the compounds of this invention in contrast to over 30 seconds for the pentaerythritol triacrylate).

EXAMPLE 5

The procedure of Example 2, Runs 1 and 2, was repeated except that the diacrylate of 2,2' [isopropylidene bis (2,6-dichlorophenoxy)] dipropylene oxide diol was the monomer instead of HET-Diol diacrylate. The results were comparable.

EXAMPLE 6

The procedure of Example 2, Runs 1 and 2, was repeated except that the monomer was HET-Diol dimethacrylate instead of HET-Diol diacrylate. The results were comparable.

EXAMPLE 7

The procedure of Example 2, Runs 1 and 2, was repeated except that the monomer was HET-Diol diitaconate instead of HET-Diol diacrylate. The results were comparable.

EXAMPLE 8

The procedure of Example 2, Run 2, was repeated except that the photoinitiator was chlorinated rubber (Hercules' Parlon) instead of Aroclor 4465. The results were comparable.

EXAMPLE 9

The procedure of Example 4, Run 12, was repeated except that the photoinitiator was benzoin methyl ether instead of Aroclor 4465. The results were comparable.

EXAMPLE 10

A thin film (0.25-mil) of 1,4,5,6,7,7-hexachloro-(2,2,1)-5-heptene-2,3-bis(methylacrylate) was applied to a sheet of aluminum plate and then exposed to a 1,200-watt ultraviolet lamp at a distance of 2 inches. The film was dried in about 3 seconds.

EXAMPLE 11

The procedure of Example 10 was repeated except that the substrate was glass. The film dried in about 3 seconds.

EXAMPLE 12

The procedure of Example 10 was repeated except that the substrate was paper. The film dried in about 2 seconds.

EXAMPLE 13

The procedure of Example 10 was repeated except that the substrate was cardboard and the monomer was 2,4,5,6-tetrachlorobenzene-1,3-dimethylacrylate. The film dried in about 2 seconds.

EXAMPLE 14

A laminate was made of a film of polymer-coated cellophane and a film of oriented polypropylene with 1,4,5,6,7,7-hexachloro-bicyclo(2,2,1)-5-heptene-2,3-bis(methylacrylate) between the two. The laminate was exposed to ultraviolet light as in Example 2, and a tight bond was effected in about 1 second.

EXAMPLE 15

A laminate was made of a sheet of copper and a film of Mylar with 2,4,5,6-tetrachlorobenzene-1,3-dimethylacrylate between the two. The laminate was exposed to ultraviolet light as in Example 2, and a tight bond was effected in about 3 seconds.

EXAMPLE 16

A red ink was prepared from 80 per cent of HET-Diol diacrylate and 20 per cent of Lithol Rubine red pigment. A glass bottle printed with this ink was exposed to a 1,200-watt Hanovia ultraviolet lamp at a distance of 2 inches. The ink dried in 3 seconds. It had excellent adhesion to glass and good grease- and rub-resistance.

EXAMPLE 17

A blue ink was prepared from 83 per cent of 2,4,5,6-tetrachlorobenzene-1,3-dimethylacrylate and 17 per cent of phthalocyanine blue. Untreated polypropylene was printed

with the ink and subjected to ultraviolet light as in Example 2. After an exposure of 3 seconds, the ink was dry and adhered well to the substrate.

5

EXAMPLE 18

The procedure of Example 12 was repeated except that the coating was a 70:30 mixture of 2,4,5,6-tetrachlorobenzene-1,3-dimethylacrylate and Aroclor 4465. The coating dried in about 2 seconds.

EXAMPLE 19

The procedure of Example 10 was repeated except that the photopolymerizable composition was a 70:30 mixture of HET-Diol diacrylate and Aroclor 4465. The film dried in about 2 seconds.

EXAMPLE 20

The procedure of Example 14 was repeated except that the adhesive was a 70:30 mixture of HET-Diol diacrylate and Aroclor 4465. A tight bond was effected in about 1 second.

EXAMPLE 21

25 The procedure of Example 14 was repeated except that the adhesive was a 70:30 mixture of 2,4,5,6-tetrachlorobenzene-1,3-dimethylacrylate and Aroclor 4465. A tight bond was effected in about 1 second.

30

EXAMPLE 22

The procedure of Example 16 was repeated except that a 70:30 mixture of HET-Diol diacrylate and Aroclor 4465 was used instead of the HET-Diol diacrylate alone. The ink dried in 2 seconds.

EXAMPLE 23

35 The procedure of Example 16 was repeated except that the HET-Diol diacrylate was replaced by a 70:30 mixture of 2,4,5,6-tetrachlorobenzene-1,3-dimethylacrylate and Aroclor 4465. The ink dried in about 2 seconds.

EXAMPLE 24

40 The procedure of Example 2, Runs 1 and 2, was repeated except that the monomer was 2,4,5,6-tetrachlorobenzene-1,3-diitaconate instead of HET-Diol diacrylate. The results were comparable.

50

EXAMPLE 25

The procedure of Example 2, Runs 1 and 2, was repeated except that the monomer was 2,4,5,6-tetraiodobenzene-1,3-diacrylate instead of HET-Diol diacrylate. The results were comparable.

55

EXAMPLE 26

60 The procedure of Example 2, Runs 1 and 2, was repeated except that the monomer was 2,3,5,6-tetrafluorobenzene-1,4-dimethacrylate instead of HET-Diol diacrylate. The results were comparable.

70

EXAMPLE 27

65 The procedure of Example 2, Runs 1 and 2, was repeated except that the monomer was the dimethacrylate of 2,2' [isopropyl-idene bis (2,6-dichlorophenoxy)] dipropylene oxide diol instead of HET-Diol diacrylate. The results were comparable.

75

EXAMPLE 28

The procedures of Examples 2 and 4 through 27 were repeated except that instead of being exposed to ultraviolet light the samples were passed on a conveyor belt beneath the beam of a Dynacote 300,000 -volt linear electron accelerator at a

speed and beam current so regulated as to produce a dose rate of 0.5 megarad.

These systems produced resinous materials of varying degrees of hardness in films from 0.5 to 20 mils thick having tacky surfaces.

EXAMPLE 29

The procedure of Example 2 was repeated except that the sample was simultaneously exposed to ultraviolet light as in Example 2 and electron beam radiation as in Example 28. The surface and interior of the film dried in 0.5 second, and the film was hard and tough.

EXAMPLE 30

The procedure of Example 29 was repeated except that the sample was exposed to ultraviolet light for two-thirds second before and two-thirds second after electron bombardment. The film was hard, tough, and flexible with a dry surface.

EXAMPLE 31

The procedure of Example 29 was repeated except that the sample was exposed to electron beam radiation before and after exposure to ultraviolet light for 0.25 second. The film was dry both internally and on the surface, and it was hard and tough.

EXAMPLE 32

The procedure of Example 29 was repeated except that the sample was exposed to ultraviolet light and then to electron beam radiation. The surface and interior of the film dried in about 1 second, and the film was hard and tough.

EXAMPLE 33

The procedure of Example 29 was repeated except that the sample was exposed to electron beam radiation and then to ultraviolet light. The surface and interior of the film dried in about 1 second, and the film was hard and tough.

While there are above disclosed but a limited number of embodiments of the process of the invention herein presented, it is possible to produce still other embodiments without departing from the inventive concept herein disclosed. It is desired, therefore, that only such limitations be imposed on the appended claims as are stated therein.

What is claimed is:

1. A radiation-curable solvent-free composition consisting essentially of (a) about 20-98 percent by weight of at least one ester of an ethylenically unsaturated acid and a member of the group consisting of 1,4,5,6,7,7-hexahalo-2,3-bis(hydroxymethyl)-bicyclo(2,2,1)-5-heptene, tetrahalobenzene-dimethanol, and 2,2'dipropylene oxide diol and (b) about 2-80 percent by weight of a photoinitiator selected from the group consisting of acyloin, acyloin deriva-

55

tives, aromatic hydrocarbons having at least one halogen atom bonded directly to the nucleus, aliphatic hydrocarbons having at least one halogen atom attached to the carbon chain, alicyclic hydrocarbons having at least one halogen atom bonded directly to the nucleus, and mixtures thereof.

2. The composition of claim 1 where the ester is an acrylate, a methacrylate, or an itaconate and the halogen is chlorine, bromine, iodine, or fluorine.

3. The radiation-curable composition of claim 1 where the ester is the diacrylate of 1,4,5,6,7,7-hexachloro-2,3-bis(hydroxymethyl)-bicyclo(2,2,1)-5-heptene.

4. The radiation-curable composition of claim 1 where the ester is the diacrylate of 2,4,5,6-tetrachlorobenzene-1,3-dimethanol.

5. The composition of claim 1 where the ester is the diacrylate of 2,2' isopropylidene bis(2,6-dichlorophenoxy)dipropylene oxide diol.

6. The composition of claim 1 where the ester is the dimethacrylate of 1,4,5,6,7,7-hexachloro-2,3-bis(hydroxymethyl)-bicyclo(2,2,1)-5-heptene.

7. The composition of claim 1 where the ester is the dimethacrylate of 2,4,5,6-tetrachlorobenzene-1,3-dimethanol.

8. The composition of claim 1 where the ester is the dimethacrylate of 2,2' isopropylidene bis(2,6-dichlorophenoxy)dipropylene oxide diol.

9. The composition of claim 1 where the ester (a) is the diacrylate of 1,4,5,6,7,7-hexachloro-2,3-bis(hydroxymethyl)-bicyclo(2,2,1)-5-heptene and the photoinitiator (b) is a mixture of bi- and triphenyls containing about 65 weight percent of chlorine.

10. The composition of claim 1 where the ester (a) is the diacrylate of 2,4,5,6-tetrachlorobenzene-1,3-dimethanol and the photoinitiator (b) is a polychlorinated diphenyl.

11. A printing ink comprising the composition of claim 1 plus a colorant selected from the group consisting of pigments and dyes.

12. A coating comprising the composition of claim 1.

13. An adhesive comprising the composition of claim 1.

14. A photopolymerizable element comprising a support and a coating thereon of the composition of claim 1.

15. An article having a dried coating of the composition of claim 1.

16. An article comprising two films adhered by the composition of claim 1.

17. A method of drying which comprises exposing to at least one source of radiation the composition of claim 1.

18. A method of laminating which comprises joining two members with an intermediate layer comprising the composition of claim 1 and exposing said intermediate layer to a source of radiation whereby said intermediate layer is dried and adhesively joins said members.

19. An article comprising two layers adhered by the method of claim 18.

UNITED STATES PATENT OFFICE
CERTIFICATE OF CORRECTION

Patent No. 3,650,885 Dated March 21, 1972

Inventor(s) Gerald I. Nass and Gerhard E. Sprenger

It is certified that error appears in the above-identified patent
and that said Letters Patent are hereby corrected as shown below:

Column 2, line 47, after "bis" insert

-- (methylacrylate) --.

Column 5, line 2, change "polyzrization"

to -- polymerization --.

Column 5, line 19, change "(methylarylate"

to -- (methylacrylate) --.

Column 5, line 25, change "1.95°" to

-- 19.5°--.

Column 9, line 53, after "2,2'" insert

-- [isopropylidene bis (2,6-dihalophenoxy)]--.

Signed and sealed this 27th day of June 1972.

(SEAL)
